ATTORNEY

UNITED STATES PATENT OFFICE.

WILLIAM SHAW, OF LAKEWOOD, OHIO, ASSIGNOR TO NATIONAL CARBON COMPANY,
OF CLEVELAND, OHIO, A CORPORATION OF NEW JERSEY.

TERMINAL CLIP.

1,147,450.

Specification of Letters Patent. Patented July 20, 1915.

Application filed August 6, 1912. Serial No. 713,571.

To all whom it may concern:

Be it known that I, WILLIAM SHAW, a resident of Lakewood, in the county of Cuyahoga, in the State of Ohio, have invented 5
5 new and useful Improvements in Terminal Clips, of which the following is a clear and exact description.

This invention relates to terminal clips to be attached to flexible electrical conductors.

The usual type of clip in use at the present time is formed by bending a flat piece of metal into proper shape and then attaching it to the end of the conductor. The 15 resulting clip has a seam on one side and does not have a neat appearance.

The object of this invention is to form a clip having no seam.

In the drawings: Figure 1 is a view of 20 the essential parts of a device for spinning the ends of the tube. Fig. 2 is a side view of a section of a metal tube having one end spun to a reduced diameter. Fig. 3 is a section taken on line A—A of Fig. 2. Fig. 4 is a view of the spun tube with a pigtail 25 therein. Fig. 5 is a section through the clip after it has been pressed. Fig. 6 is an end view of the clip shown in Fig. 4 after it has been pressed. Fig. 7 is a view of the 30 clip after it has been pressed and the slot cut. Fig. 8 shows a clip with a hole instead of a slot. Fig. 9 is a sectional view of a clip and attached pigtail in which the whole tubular clip has been pressed flat.

35 Referring to Fig. 1 a tube 1 is represented in a more or less diagrammatic way as being rotated by a chuck 2 against two wheels 3, 4. As is well known, the tube will be spun to a point 5 if it is rotated at a high speed 40 and pressed to the right between the two wheels or is pressed between the wheels in a direction perpendicular to the plane of the paper. The wheels 3, 4 are free to rotate, but have no rotative tendency except 45 when engaged by the rotating tube 1. Since no claim is made in this application to the apparatus for spinning the tubes, no further description of it is necessary.

After the tube 1 has been spun at one end

and cut off as shown in Figs. 1 and 2, a wire 50 conductor 6 is inserted through the hole 7 and spread out as at 8. All of the tube 1 but the spun end 5 is then pressed or flattened by any means as shown in Fig. 5. A front view of the clip after it has been flattened 55 is given in Fig. 6. The opening 9 which may be either a slot or hole, is then cut in the clip.

Instead of flattening all but the spun end 5 of the tube as in Figs. 5 and 6, the entire 60 tube may be flattened. This is shown in Fig. 9. However, the latter may tend to cause the wires to break under constant bending of the conductor in use, and hence the clip shown in the former figures is 65 preferable.

The clips as described are easily made and attached to pigtails for brushes or other conductors, and are so securely held to the conductor that they cannot be pulled off in 70 usage.

The clips are also more neat in appearance than the old type.

Having described my invention what I claim is:

1. A terminal clip consisting of a flattened tube with a constricted end, a cable clamped between the sides of the tube and extending through the constricted end.

2. A terminal clip consisting of a flattened 80 tube with a constricted end and a cable clamped between the sides of the tube and extending through said end, the other end of said flattened tube having an opening therethrough.

3. A terminal clip consisting of a flattened body portion and an end portion with a constricted opening and a flexible cable extending through the said opening and clamped between the sides of the body portion only.

4. A terminal clip consisting of a tube with a flattened body portion and a substantially conical end and a flexible cable extending through the said end and clamped 90 between the sides of said body portion.

5. A terminal clip consisting of a tube with a flattened body portion and an end

portion with a constricted opening, a flexible cable extending through the said opening and clamped between the sides of the body portion only, said end portion extending to one side of the central longitudinal axis of the body portion.

In testimony whereof I have hereunto

signed my name in the presence of two witnesses.

WILLIAM SHAW.
